UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A GOBLET OR SIMILAR ARTICLE.

46,322.

Specification for Design.

Patented Aug. 25, 1914.

Application filed May 20, 1914. Serial No. 839,909. Term of patent 3½ years.

To all whom it may concern:

Be it known that I, ANDREW J. SANFORD, a citizen of the United States, residing at Newark, Ohio, have invented a new, original, and ornamental Design for a Goblet or Similar Article, of which the following is a specification, reference being had to the accompanying drawing, forming part thereof.

Figure 1 is a side elevation of a goblet illustrating my new design; Fig. 2 is a horizontal section taken on the line 2—2 of Fig. 1, looking upwardly. Fig. 3 is a horizontal section taken on the line 3—3 of Fig. 1, looking downwardly.

This invention has for its chief characteristic, a stem projecting from a base and sup-

porting the vessel, the sides of which are composed of a series of panels which are wider at the top and bottom and narrowed toward their midlength, the sides of the vessel itself being provided with a series of panels gradually converging from a point to the midlength of the body of the vessel downwardly toward the stem. The upper portion of the vessel is plain.

I claim:

The design for a goblet or similar article, substantially as shown and described.

ANDREW J. SANFORD.

Witnesses:

MAUD BETTS,
H. C. MUELLER.
